UNITED STATES PATENT OFFICE.

WALMAC E. EDWARDS, OF GOLDFIELD, NEVADA.

TOOL-RETAINER FOR DRILLING-MACHINES.

1,229,424.

Specification of Letters Patent. Patented June 12, 1917.

Application filed November 7, 1916. Serial No. 130,053.

To all whom it may concern:

Be it known that I, WALMAC E. EDWARDS, a subject of the King of Great Britain, and a resident of Goldfield, in the county of Esmeralda and State of Nevada, have invented a certain new and useful Improvement in Tool-Retainers for Drilling-Machines, of which the following is a specification.

The present invention relates to an attachment to be applied to drilling machines for holding the drill steels or tools in the socket when the drilling machine is tilted downwardly, or when the drilling tool is being extracted from a bore.

The drilling machines which are now commonly used, usually of the pneumatic type, are provided with spring muzzles or retaining yokes which engage the shanks of the tools, and which are held in engagement therewith by studs projecting laterally from the forward head of the tool. The yokes are held in interlocking engagement with the tools by springs, the latter frequently being compressed to their full extent to release the yokes under the vibration of the tool when the latter is being extracted.

It is an object of the present invention to provide an attachment of this character which will prevent the accidental displacement of the retaining yokes, and to provide a positive lock for holding the yokes about the tool under all conditions, the lock being readily releasable when it is desired to extract the tool.

It is the further aim of the present invention to provide an attachment of this character which may be applied to stock machines which are already manufactured, and which therefore does not necessitate any special formation of the barrel or forward head of the drilling machine.

Other objects and advantages of this invention, as well as those above enumerated, will be brought out more particularly in the following detailed description of the present preferred embodiment of this invention, the same being illustrated in the accompanying drawings wherein:

Figure 1 is a side elevation of the outer end of a drilling tool, the tool retainer of the present invention being applied thereto.

Fig. 2 is an enlarged side elevation of the same, taken at right angles to the showing in Fig. 1.

Fig. 3 is an enlarged view similar to Fig.

1, showing in dotted lines the tilting of the retaining jaws to release the tool steel.

Fig. 4 is a side elevation of the outer end of a drilling tool with a modified form of the retainer of this invention applied thereto, the view showing a latchlock for holding the retainer in place.

Fig. 5 is a similar view showing the latch in its locking position, the view also showing the socket end of the tool disengaged from the drilling machine.

Fig. 6 is a detail perspective view of the front head of the drilling machine according to the modification shown in Fig. 5.

Fig. 7 is a detail perspective view, enlarged, of the retaining jaw of the present invention according to the modification shown in Fig. 5.

Fig. 8 is a detail perspective view, enlarged, of the locking latch which is applied as shown in Figs. 4 and 5.

Fig. 9 is a side elevation of the outer or front head of a drilling machine, showing a modified construction of the tool retainer.

Fig. 10 is a similar view, showing the retainer in releasing position, and showing the shank of the tool detached from the drilling machine.

Fig. 11 is a side elevation of the drilling machine having the tool retainer of Fig. 9 applied thereto, the figure being taken at right angles to the showing in Fig. 9.

Fig. 12 is a side elevation of the front head of the drilling machine, showing a modification in the mounting of the pivot and retaining lugs carried by the barrel.

Fig. 13 is a detail perspective view, enlarged, of one of the lug-carrying members.

Fig. 14 is a top plan view of one side of the front head of the drilling machine, showing one of the lug-carrying members applied thereto.

Referring to these drawings, wherein like parts are designated by similar characters of reference throughout the several views, one form of the present invention is shown in Figs. 1 to 7 inclusive, and wherein a drilling machine 10 is provided with the usual head 11 connected to the drilling machine by spring rods 12 which slidably pass through ears 13 projecting from the inner end of the head 11, and which carry springs 15 bearing against the ears 13 to resiliently support the head. A drill steel or tool 16 has the usual shank 17 and an enlargement or collar 110

18 which surrounds the shank 17 and is adapted for engagement against the outer end of the head.

The head 11 is provided at opposite sides 5 with radially disposed lugs 19 adapted to pivotally support a jaw 20. The jaw 20 is in the form of a yoke or bail at its inner end engaging about one side of the head 11 and provided with pivot ears 21 for engagement 10 over the lugs 19. The jaw 20 is provided upon its forward end with a tool-engaging plate 22 which is slotted radially, as at 23, to freely receive the shank of the tool 16 beyond the collar 18. This plate 22 is spaced 15 forwardly from the head 11, and when applied to the tool 16, permits of the free vibration of the same. The slot 23 of the plate 22 extends toward the closed side of the yokes of the jaw, and is thus releasable 20 from the tool by the swinging outwardly and forwardly of the jaw.

In Figs. 1, 2 and 3 of the drawings, there is shown a bail lock for securing the jaws in closed position upon the tool. The head 25 11 is provided with a bail 24 which has collars 24^a on its ends mounted to slide and tilt on the rods 12 at the opposite side of the head 11 adjacent to the ears 13 thereof. The bail 24 is adapted to extend around the 30 head 11 and over the yoke of the jaw 20, and is provided at its intermediate portion with a finger loop 25 for swinging the bail and binding the latter over a lip or projection 26 which extends outwardly from the jaw 20. The bail 24 is adapted to hold the jaw 20 from swinging about the pivot lugs 19. Any attempt to withdraw the tool 16 from the head 11, causes the shank 17 to slide outwardly from the socket in the head 11, and 35 40 the collar 18 to bind against the retaining plate 22. The slot 23 is of a size which loosely receives tool 16 therethrough, but which is of less width than the diameter of the collar 18. Pressure upon the tool 16 is 45 transmitted through plate 22 to the pivot 19 of the jaw 20, and the retaining bail 24 is relieved of all strain incident to pressure placed upon the tool. The jaw 20, therefore, will not become accidentally unlocked 50 or free the tool during the vibration of the machine.

In Figs. 4 to 8, inclusive, there is shown a slightly modified form of jaw, and a modified form of locking means therefor. The 55 jaw 20^a, as shown in Fig. 7, is of substantially the same general form as shown in Figs. 1, 2 and 3. The inner end of the jaw 20^a is provided with a slot 27 in each side, the slots opening at their forward ends 60 through the edges of the jaw. Intermediate the ends of the jaw 20^a, and in the opposite sides thereof, are provided slots 28 closed at their opposite ends and arranged in longitudinal alignment with the slot 27. The 65 pivot lugs 19 of the head 11 are adapted for

engagement in the closed slots 28, and retaining lugs 29 are arranged at the opposite sides of the head 11 for engagement in the open slot 27. The lugs 19 and 29 are so spaced apart that when the lugs 19 are disposed in the forward ends of the slots 28, the retaining lugs 29 register with the open forward ends of the slot 27. This arrangement of the slots and lugs is shown to advantage in Fig. 4. The jaw 20^a is adapted 70 to be slid forwardly upon the head 11 to dispose the lugs 19 and 29 in the rear end of the slots 27 and 28, as shown in Fig. 5. When in this position, the retaining lugs 29 hold the jaw 20^a from swinging about the 80 pivot lugs 19.

The jaw 20^a is provided at its inner end, and intermediate the edges thereof, with a locking latch, the same comprising a relatively broad thumb lever 30 pivoted at its inner end upon a transversely extending pin 31 and provided upon its inner side with a lug or bolt 32. As shown in Fig. 4, this locking latch is adapted to be tilted outwardly from the adjacent side of the head 90 11 to permit of the free sliding movement of the jaw 20^a into and out of closed position. When the jaw 20^a is moved into the position shown in Fig. 5, the thumb lever 30 is adapted to be swung down through a slot 95 33 formed in the rear edge of the jaw 20^a, and to engage in a depression or recess 34 formed in the adjacent side of the head. From Fig. 5 it will be noted that the thumb lever 30 is prevented from swinging down 100 into engagement with the head, and the bolt 32 is inclined rearwardly at a slight angle and is of greater length than the depth of the slot 34. This latch is adapted to bind frictionally in this position and to thus retain the jaw 20^a from swinging or sliding out of engagement with the tool. In Fig. 5 there is shown the relative length of the shank 17 of the tool, and the distance between the retaining plate 22 of the jaw and the folded end of the head 11. Sufficient space is left between the plate 22 and the head to permit of the free vibration of the tool when in use.

In the form of the present invention 115 which is shown in Figs. 9, 10 and 11, the features of this invention are shown as applied to the ordinary spring muzzle which is at present usually furnished as a part of drilling engines. In this instance, the pivoted jaw is made up of the usual yoke 35 which engages the shank of the tool 16. The ends of the yoke 35 pass through eyes 36 formed through the outer ends of a pair of clevises or plates 37 which are disposed 120 against the opposite sides of the head 11. These plates 37 are provided, as shown in Fig. 7, with the forward closed slots 28 and the rear open slots 27. The free ends of the yoke 35 pass beyond the eyes 36 and are pro- 125 130

vided with helical springs 37 engaging the eyes 36 and held thereagainst by adjustable retaining nuts 38. The plates or clevises 37 form the opposite sides of the pivoted jaw, 5 and are held in engagement with the retaining lugs 29 by the springs 38' which at all times urge the plates 37 forwardly, and particularly when the collar 18 of the tool engages the yoke 35. With this construction 10 it is thus seen that the harder the tool binds against the yoke 35, the tighter, through the lugs 29 locks the pivoted jaw from turning. This construction differs from the usual spring muzzle employed in 15 that the yoke 35 is held in position upon the tool only by reason of its extensive mounting on the head 11, and when the drilling engine is turned to space the yoke 35 downwardly, it frequently becomes disengaged from the tool under the vibrating action thereof.

In Figs. 12, 13 and 14, there is shown a modified arrangement of the lugs at the opposite sides of the head 11. Where it is desired to apply the improvements of the present invention to stock machines which are not provided with the pivot lugs 19 or the retaining lugs 29, the devices of Fig. 12 may be employed. Surrounding each rod 30 12, at the side of the head 11, is a sleeve 40. The upper end of the sleeve 40 is adapted to engage about the ear 13, and is open at its inner side so as to fit snugly about the ear. The lower end of the sleeve 40 is open at its 35 outer side and is adapted for engagement against the head 11, providing a relatively small space or slot 41 between the sleeve and the head. The inner closed side of the sleeve 40, the lower end of the sleeve, is provided 40 with spaced lugs 19^a and 29^a. These lugs are of such length that at their free ends they bear against the adjacent side of the head 11, and serve the dual purpose of pivotally supporting the retaining jaw of this 45 invention, and of also locking the same when in closed position. The sleeves 40 are of such internal diameter that they freely receive the springs 14 therein, and permit of the adjustment of the springs by the turning 50 of the nuts usually employed upon the outer ends of the rod 12. Within the upper ends of the sleeves 40 are collars 40^a adapted to embrace the rods 12 between the ears 13 and the adjacent ends of the spring 15 to 55 hold the sleeves 40 in place. A preferably metal strap 42 is passed around the side of the head 11 and is secured at its opposite ends to the sleeve 40 for retaining the same from lateral displacement from the head.

60 It is of course understood that various other changes and modifications may be made in the structure contemplated by the present invention without departing from

the spirit thereof, such changes and modifications being restricted only by the scope of 65 the following claims.

I claim:

1. A tool retainer for drilling engines comprising a jaw pivoted upon the front head of the drilling engine and adapted to 70 engage about a tool to hold the tool in said head, and a locking member between said front head and said jaw adapted to engage the latter and retain it in engagement with the tool.

2. In a drilling engine, the combination with the forward head of the drilling engine, of a yoke engaging about one side of said head and having a forwardly projecting portion slotted to receive the shank of a 80 tool therethrough, a pivotal support for the yoke carried upon said head, said yoke being adapted to be swung about said support to engage and disengage the forward end thereof with the tool, and a locking member 85 carried by the head adapted to engage the yoke when swung into engagement with the tool to hold the yoke from disengagement therefrom.

3. In drilling engines, the combination 90 with a head having pivot lugs at its opposite sides, a yoke engaging about one side of said head and having pivot ears engaging said lugs to pivotally support the yoke, said yoke having a forwardly projecting portion including a plate provided with a slot extending radially in one direction to receive the shank of a tool therethrough, the slot opening toward the closed side of the yoke and adapted to release the tool upon the swinging of the yoke away from the side of the head, and locking means carried by the head and engaging the yoke when the latter is swung into engagement with the tool, to hold the yoke against displacement by vibration of the machine.

4. In drilling engines, the combination with a head, a jaw pivoted upon said head and adapted for engagement at its outer end with a drill steel, said jaw provided 110 upon its inner end with an outwardly extending lip, and a bail hinged upon said head and adapted for interlocking engagement with said lip to retain the jaw from swinging out of engagement with the tool.

5. In drilling engines, the combination with a head, a jaw pivoted on said head and adapted for engagement at one end with a drill steel to retain it in the head, said jaw having a projection upon its opposite end, 120 a bail hinged upon said head inwardly of said jaw, and adapted for engagement over said projection to hold the jaw from tilting out of engagement with the tool.

WALMAC E. EDWARDS.
